FERDINAND W. KROGH, OF SAN FRANCISCO, CALIFORNIA; CARL A. KROGH AND OSCAR POULSEN ADMINISTRATORS OF SAID FERDINAND W. KROGH, DECEASED.

DEEP-WELL PROPELLER-SCREW PUMP.

1,342,551.

Specification of Letters Patent.

Patented June 8, 1920.

Application filed October 18, 1916. Serial No. 126,409.

To all whom it may concern:

Be it known that I, FERDINAND W. KROGH, of San Francisco, California, have invented certain new and useful Improvements in 5 Deep-Well Propeller-Screw Pumps, whereof the following is a specification.

My invention relates more particularly to improvements in deep well pumps wherein the pressure is increased in successive steps 10 by means of power given from a pair of co-operating compensating propellers revolubly mounted on the same shaft, and pitched in reverse directions, and it consists of an improved series of suitably proportioned and 15 curved blades for impelling the water and of intervening sections formed into diverting channels for directing the flow of the water.

The objects of my invention are to provide a simple, practical and operative pump 20 that will efficiently and constantly discharge an unvariable stream by means of a pair of suitably arranged propelling blades, having diverting waterways interposed therebetween; also to provide in combination there- 25 with an automatic compensating device in the form of an adjustable valve pivoted to the main shaft that will regulate and control the water pressure and thereby balance the pump shaft.

30 Other objects of my invention will become apparent as the description progresses.

In the two sheets of drawings here annexed forming a part of this application in which:

35 Figure 1 represents a vertical section taken through a vertical propeller screw pump constructed in accordance with this invention.

Fig. 2 is a cross section taken on line *a—a* 40 of Fig. 1.

Fig. 3 is a cross section taken on line *b—b* of Fig. 1.

Fig. 4 is a modification and elaboration of Fig. 1 showing the means of lubrication, 45 and the compensating device for automatically balancing the opposed co-operating series of propeller blades, and the shaft.

Fig. 5 is a cross section taken on the line *c—c* of Fig. 4.

50 Fig. 6 is a cross section taken on the line *d—d* of Fig. 4 and

Fig. 7 is a vertical section of a thrust bearing for supporting the weight of the shaft.

In detail the construction illustrated in

the drawing, Fig. 1 shows the outer casing 55 of a pump designated by the numeral 1 having the inner, tubular shaped casing 2, spaced from the outer casing 1 and held in position by the cored inlet openings 3.

The outer casing 1 is flanged at its top- 60 most end as at 4 to provide a means for connecting the pipe.

The bottom 5 is rounded at 6 to diminish the frictional tendencies and has the bearing 7 formed therein for the shaft 8, and to re- 65 ceive any end thrust which the said shaft might have.

Securely fastened to the shaft 8 are the hubs 9 provided with a plurality of suitably shaped spiral blades 10. The flat semi-elliptic braces 11 securely fastened in a slanted position within the collar 12, which is rigidly secured to the inner casing 2, are interposed between each set of spiral blades 10 and prevent any water that is being pumped 75 from swirling. As can be easily perceived in the drawing (Fig. 1) the shaft 8 has two series of spiral blades 13 and 14, correctly spaced with reference to the inlets 3, the pressure faces of the opposite series of blades 80 are directly opposed. The blades 10 on the lower series 13 are so formed that when revolved, the liquid contained in the inner casing will be forced downward, whereas the series 14, when revolved in the same direc- 85 tion, as the lower series, will force the liquid upward. This is due to the fact that the blades are spirally shaped, and pitched in opposite directions.

The action of the described pump is some- 90 what similar to the "double acting pump" now in common use in that, a double pumping action results, but pulsation is absent, the latter being a continuous flow, which differs materially from the alternating ac- 95 tion of the former.

The operation of this pump is as follows: The pump is lowered into a well so that water enters the casing 2 through the inlet port 3, and entirely submerges the blades 10. 100 When the blades commence to revolve, they are so directed that they create a downward thrust at 13 and an upward thrust at 14 and force the liquid through the outlet 15. The liquid in each case is forced away 105 from the inlets 3. As the liquid is being pushed downward by the propeller series 13, it encounters the concave surface 6 of

bottom 5, and not being able to go back through the tubular casing 2, is deflected upward in the channel 16 formed by the casing 2, spaced from the outer casing 1. The liquid from the propeller series 14 has been forced upward synchronously with the water from series 13 that has been forced downward so that the two liquids meet at the outlet 15, and continue on through the connecting pipe (here not shown). As the water is pressed forward by the revolving blades 10 an action is imparted to it which action is broken by the interposed braces 11. The braces 11 are a valuable asset in that they destroy any whirling motion of the liquid.

The plurality of spiral blades contained in each of the series 13 and 14 are so fastened on the shaft 8 that they are balanced perfectly. Were the series blades 10 not affixed in a balanced manner, an undue strain would be imposed on one or the other propellers and would deter its mechanical abilities.

25 A modification is shown in Fig. 4 in which 17 denotes the main pump casing inclosed at its lower end by the enlarged casing 18, which may be connected to a suction pipe. The tubular casing 17 is turned at 19 so that the continued section 20 is parallel with the main pump casing. The ends of the casing 17 and 20 terminate in the outlet chamber 21. In the lower bent portion 19 a bearing 22 is formed for the shaft 23, having the liquid propelling blades series 24 and 25 attached thereon with the deflectors 26 interposed therebetween. The casing 17 has the inlet ports 27 formed on its outer diameter.

40 The shaft 23 as shown in Fig. 4 is held in alignment by the bearing 28 located below the upper bearing 29, formed in the outlet chamber 21, and the lower bearing 22, upon which the shaft moves freely according however to the variations in the pressure of the incoming liquid exerted on the propellers of series 24 or 25 and its movements operate the compensating device consisting of arm 30 pivoted to the extended portion 31 above the chambers 21 and pivotally connected to shaft 23 at 32 and provided with connecting rod 33 having the cone shaped gate 34 secured thereon to diminish or increase the pressure of liquid passing through the port 35.

55 The operation of the compensating device is as follows. The port 35 being closed as shown in Fig. 4 by the downward movement of the shaft then the downward pressure of water from the propeller series 24 against the gate 34 will become greater than the upward pressure of water from the propeller series 25, that will cause the shaft 23 to move upward and through the arm 30 and rod 33, the gate 34 will move upward

and consequently open the port 35 thus releasing the water pressure and thereby causing the upward water pressure from the propellers series 25 together with the weight of the shaft, etc., to move the latter downwardly and vice versa until the shaft 23 finds its equilibrium, thus automatically balancing the shaft.

70 Rotation is imparted to the shaft 23 by a belt running on the pulley 36, or motor 75 connected to the shaft if desired.

The manner of lubricating deep well shafts has heretofore been a source of endless trouble, but it is well taken care of in this case by the positive force pump 37 having the pipe 38 with its tributaries 39 running to all the bearings.

80 Around the propellers' shaft as shown in Figs. 1 and 4, is a pipe casing 40, which is located between the upper series 25 of the propellers and the upper bearing 29 of the shaft and carries the waste oil leaking out from the bearings to the discharge pipe 41.

85 As shown in Fig. 1 the pipe casing 40 is provided above the collar 12 with packing 42 forced down by a weight 43, to prevent the oil at that point from leaking out into the outer casing.

90 It will be noticed in Fig. 1 that the number of propellers at the top of casing 2 is less than at the bottom, because in addition to the balance of the water on the upper propeller, it also has to carry the shaft with all its couplings and connections. This cannot be accurately done. It will, therefore, 100 require an adjustable mechanical thrust bearing, to take the unbalanced weight of same and keep it in its proper place so that the propeller hubs will have no rubbing surface.

105 In Fig. 7 I have shown an example of such thrust bearing consisting of two frames 44, and 45 forming a part of the main casing of the pump and projecting therefrom around the rotating shaft 8 thereof.

110 Upon the shaft 8 is a collar 46 adjustably secured thereon between the projecting frames 44 and 45 by means of a set screw 47 or otherwise, and on each side of the collar 46 are two loose rings 48 provided therebetween with ball bearings 49 to form anti-frictional means against one of the projecting frames 44 and 45 to which the shaft may move.

115 Having thus described my invention, and an embodiment of it, in the full, clear and exact terms required by law, and knowing that it comprises novel, useful and valuable improvements in the art to which it pertains, I here state that I do not wish to be limited to the precise construction and arrangement of the several parts, as herein set forth, as the same may be variously modified by a skilled mechanic without departing from the spirit of the invention.

What I claim and desire to secure by Letters Patent of the United States, is the following to-wit:—

1. In combination with a screw pump; a casing having an outlet port; an inner casing having an intake port; a shaft mounted in said inner casing having securely fastened thereon a set of propeller screws of which one set of pressure faces is mounted 10 on the reverse of the other in an inclined position; a continuation of said inner casing on the outside running parallel to said inner casing; a chamber covering the ends of said casing; and a valve covering the ends of 15 said parallel pipe controlled by a lever arm attached to the main shaft.

2. In combination with a screw pump; a casing having an outlet port; an inner casing with inlets therein, having a lower extended portion bent and made parallel with the said inner casing so that the ends lie in the same plane; a chamber covering said open pipe ends; a shaft with two sets of propeller screws securely mounted thereon having 20 the blades of one set attached the reverse of the other, revolvably running in said inner casing; a deflecting means interposed between said blades; and a valve covering the end of said bent parallel casing, having an arm attached thereto that is pivotally mounted on the shaft and pivotally secured to the casing of said chamber, and a means 25 for lubricating the bearings of said shaft.

3. In combination with a screw pump; a casing having an outlet port; an inner cas-

ing with inlets therein, having a lower ex- 35 tended portion bent and made parallel with the said inner casing so that the ends lie in the same plane; a chamber covering said open pipe ends; a shaft with two sets of propeller screws securely mounted thereon 40 having the blades of one set attached the reverse of the other, revolvably running in said inner casing; a deflection means interposed between said blades; a valve covering the end of said bent parallel casing, having an 45 arm attached thereto that is pivotally mounted on the shaft and pivotally secured to the casing of said chamber, and a means for lubricating the bearings of said shaft.

4. In combination with a screw pump; a 50 casing having an outlet port; an inner casing with inlets therein, having a lower extended portion bent and made parallel with the said inner casing; a shaft with two sets of propeller screws securely mounted there- 55 on having the blades of one set secured the reverse of the other, revolvably running in said inner casing; a deflection means interposed between said blades; a valve for said bent parallel casing, and means on said shaft 60 to control said valve.

In testimony that I claim the foregoing, I have hereto set my hand this 13 day of Oct., 1916, in the presence of two witnesses.

FERDINAND W. KROGH.
